(57) **CLAIM**

The ornamental design for an orthodontic bracket, as shown and described.

DESCRIPTION

FIGS. 1 to 7 are perspective view, front view, rear view, left view, right view, top plan view, and bottom plan view of a first embodiment of an orthodontic bracket in accordance with our new design;

FIGS. 8 to 14 are perspective view, front view, rear view, left view, right view, top plan view, and bottom plan view of a second embodiment of an orthodontic bracket in accordance with our new design;

FIGS. 15 to 21 are perspective view, front view, rear view, left view, right view, top plan view, and bottom plan view of a third embodiment of an orthodontic bracket in accordance with our new design;

FIGS. 22 to 28 are perspective view, front view, rear view, left view, right view, top plan view, and bottom plan view of a fourth embodiment of an orthodontic bracket in accordance with our new design;

FIGS. 29 to 35 are perspective view, front view, rear view, left view, right view, top plan view, and bottom plan view of a fifth embodiment of an orthodontic bracket in accordance with our new design;

FIGS. 36 to 42 are perspective view, front view, rear view, left view, right view, top plan view, and bottom plan view of a sixth embodiment of an orthodontic bracket in accordance with our new design; and,

FIGS. 43 to 49 are perspective view, front view, rear view, left view, right view, top plan view, and bottom plan view of a seventh embodiment of an orthodontic bracket in accordance with our new design.

The broken lines in the drawings depict portions of the orthodontic bracket that form no part of the claimed design.
